UNITED STATES PATENT OFFICE.

PAUL EEBLING, OF NEW YORK, N. Y.

CROSSING BRIDGE.

Application filed July 9, 1926. Serial No. 121,391.

The present invention relates to improvements in bridges, particularly bridges to be used at street crossings, at conflagrations, etc., and it is the principal object of the invention to provide foldable or collapsible bridges of this type which may readily be set up and removed without the employ of special complicated and cumbersome apparatus.

10 Bridges constructed according to my invention are particularly well adapted for use at street crossings and intersections where heavy traffic prevails during part of the day, they may just as well also be used at railroad crossings or the like. They allow a safe passage of pedestrians at the hours of the heaviest traffic and may readily be folded and set aside without obstruction for the traffic and the view.

20 Another object of the invention is the provision of foldable or collapsible bridge members at street crossings or the like allowing even the transfer of vehicles when required, and adapted to be used in any required number doing away with stairs, etc., as they can be set up at any desired angle to the streets.

A further object of my invention is the provision of a foldable or collapsible bridge composed of a plurality of members according to occasion and necessity, which may conveniently be used to facilitate the escape of persons during a conflagration from a burning building, etc., into the street or into buildings across the street.

30 A still further object of the invention is the provision of a foldable or collapsible bridge having vertical posts allowing the convenient display of advertising signs and matter, as well as serving as lamp posts, flag posts or posts for holding decorations of any kind during parades and festivals.

It is furthermore one of the objects of my invention to provide a foldable and collapsible bridge, the roadway of which, while strongly constructed to carry a great number of pedestrians and other loads, can readily be folded or wound upon or from suitable rollers or other means in order to avoid obstruction of the view when the bridge is not in use.

50 The mechanism for effecting the folding and unfolding of the roadway can be readily

operated and may either be combined with the bridge or may be arranged in suitable pits below the street level.

55

The foldable bridges according to my invention are equipped with foldable hand rails or balusters, and suitable supports for the roadways when in operation, while easily detachable cables ensure stability. They may be set up in a plurality of members either across a street, permitting the traffic to pass through the lower parts thereof, or they may have walls allowing a placing of the bridge when not in use against house walls, etc., without obstruction of the view from the windows thereof. They may have a central post from which the bridge members extend to both sides and held by suitable cables, or they may be counterbalanced by suitable weights, etc.

65

70

75

These and other objects and advantages of my invention will become more fully known as the description thereof proceeds, and will then be specifically pointed out in the appended claims.

In the accompanying drawings forming a material part of this disclosure:

Fig. 1 is a side elevation of a bridge element constructed according to my invention.

80

Fig. 2 is a top plan view thereof.

Fig. 3 is a section on line 3—3 of Figure 1.

Fig. 4 is a side elevation of a modified form of a bridge element constructed according to my invention.

85

Fig. 5 is a section on line 5—5 of Figure 4.

Fig. 6 is a top plan view seen in the direction of the arrowed line 6—6 of Figure 4.

90

Fig. 7 is a side elevation of another modified form of my invention.

Fig. 8 is a top plan view thereof, seen in the direction of the arrows 8—8 of Figure 7.

Fig. 9 is an end view thereof seen in the direction of line 9—9 of Figure 7.

95

Fig. 10 is a side elevation of a still further modification of my invention.

Fig. 11 is a top plan view thereof.

In the form of my invention illustrated in Figures 1, 2 and 3, the bridge element 100 comprises a base 10, carrying lugs 11 securely attached thereto and forming the base or place of attachment for the lower ends or feet of vertical, parallel posts 12,

pairwise arranged in spaced relation and additionally secured to the base 10 by means of angle irons or brackets 13, or the like.

Intermediate their ends, at a suitable height from the street level, horizontally and pairwise arranged spaced and parallel girders 14 or the like are pivoted intermediate their ends to the posts 12, as at 15, and links 16 pivoted at one end, as at 17, to the side girders 14, and at their opposite ends to lugs 18 on the edges of posts 12, connect the latter with the girders.

The horizontal girders can be set at any desired angle or inclination to the posts and held therein, to allow the stepping of pedestrians thereon without the necessity of employing supplementary stairs etc., and as many sets of bridge elements as required may be used in order to ensure safe passage across a street etc. It will be clear that the end sections or units of the bridge elements will be in tilted position so that pedestrians may conveniently step thereon or off. In some exceptional cases where local conditions require this, the end sections are used in their horizontal position and access to the same is provided by means of suitable stairways etc.

At one end the sets of bridge elements are provided with cross-bars 19 to which the vertical supports 20 are pivotally secured, the lower ends of which are detachably attached by means of pins 21 or the like to suitable lugs 22 or the like on the base 10. The parallel girders 14 are spaced apart and connected by means of suitable brackets at suitable intervals to the pins 24 to which one end of cables 25 is attached, said cables being guided over rollers 26 or the like at the upper ends of posts 12, and have their other ends detachably secured to suitable eyes 26 or the like on the base 10.

Other, holding cables 27 are attached at one end to pins at the ends of the girders 14, while their opposite ends are fastened to suitable means on posts 12.

The cables 28 are attached at one of their ends to eyes on the opposite side of the posts 12, and at their other ends to eyes 29 on the girders 14.

Balusters or hand rails 30 are removably held in the upper ends of vertical rail posts 31 arranged in suitable numbers and intervals, and removably attached at their lower ends to brackets 32 on girders 14.

The roadway 33 proper for the pedestrians etc. is preferably made of metal or other strong material, and is of the roller type, composed of a plurality of interconnected slats 33' or the like, adapted to be wound upon or from roller 34 journaled at the ends of the girders 14.

This roadway 33 is unwound from and wound upon the roller by means of cables 35 or the like, wound upon or from a roller

36 also journaled with its ends in the girders 14 and having a crank 37 secured thereto at the outer end projecting beyond the girders.

A plurality of guide rollers 38 guide the slats of the roadway, the outer ends of which on the sides thereof are preferably guided within suitable grooves in the inner opposite side faces of the girders 14 or along strips attached thereto, while a longitudinal strip 39 guides and supports the roadway in the center thereof.

In the modified form of my invention illustrated in Figures 4, 5 and 6, each bridge element has a vertical wall 40 adapted to be placed against a house wall etc. and secured at its lower end to a base-plate or frame 41 against which it is braced by a bracket or brackets 42 or the like.

The roadway in this form of my invention consists also of a plurality of horizontal, parallel and spaced side girders 43 pivotally attached at one end to suitable brackets 44 on the vertical wall 40, and braced against the same by means of links 45 or the like, pivotally attached at one end to the girders, and at their opposite ends to suitable ears 46 on wall 40.

Cables 47 secured at one end to the eyes 48 on wall 40 and at their opposite ends to the girders 43, as at 49, hold the girders in their horizontal position, while other cables 50 attached to suitable pins on girders 43, are guided over rollers 51 near the upper end of wall 40 and behind guides 52 to rollers or pulleys 53, the shafts 54 of which extend over the pulleys at one side and carry a crank 55 or the like.

Rail posts 56 are pivotally attached at their lower ends to the girders 43 and carry at their upper ends removably, the balusters 57.

The roadway proper or walk for the pedestrians etc. consists in this form of my invention also of a plurality of interconnected parallel cross-slats 58 adapted to be rolled upon or from a roller 59 journaled in brackets 44 and adapted also to be operated from cables 60 at the end of the roadway and wound about a roller 61 on a shaft journaled between girders 43 and extending at one end beyond the same to carry a crank arm 62.

In the form of my invention illustrated in Figures 7, 8 and 9, the vertical bridge posts 63 have their lower ends supported in blocks 64 on a base 65, above a pit formed by U-posts 67, 68 supported on a ground plate 69, and designated 66.

The bridge members 70, 71, have their inner ends pivotally connected to links 72, and each member consists of two horizontally arranged parallel spaced girders.

A hand rail 73 is removably supported by a plurality of post rails 74 or the like, pivotally attached at their lower ends to mem-

ber 71, so that it can be folded against the same. The other member 70 has near its outer end, pivotally attached thereto, as at 75, a foot post 76, the lower end of which 5 is detachably secured to a suitable bracket 77 on the ground.

Cables 78 are attached at one end to member 70 and guided over rollers 79 at the post 63 and their other ends are attached, 10 as at 80 to member 71. Other cables 81 have their outer ends secured to eyes on member 71 and are guided over pulleys 82 at the cross-head 83 on the upper end of post 63 on one side thereof. The other side of the 15 post can be utilized for the suspension of street lamps 84 or the like or for the support of signs of any suitable form, illuminated or not for advertising purposes or the like, as indicated at 85.

20 The free end of cable 81 is guided through guide loops 86 or the like to a roller 87 having its shaft extended to the outside, and carries an operating crank 88.

In the form of my invention illustrated in 25 Figures 7, 8 and 9, the roadway for pedestrians etc. is composed of an endless band 89 of any strong material suitable for the purpose or the like, which is suitably and safely guided to support certain loads, and to the 30 outer ends of which cables 90 are attached, adapted to be wound about a roller 91 supported in the posts 66 in suitable brackets 92 and the roller shaft is extended towards one side and carries a crank arm 93. The 35 endless band is guided over suitable guide rollers and its center is supported by a longitudinal band or the like 94.

In the modified form of my bridge members, illustrated in Figures 10 and 11, the 40 vertical posts 95 are secured to a base 96 by means of brackets 97 or the like, and the horizontal girders 98 are held in their position by means of cables 99 secured at one end to the girders 98 as at 100, they are guided 45 over pulleys 101 on top of posts 95, and carry at their ends weights 102. A frame 103 carrying at its rear end a weight 104 is attached to the girders 98, as at 105, which are spaced at this place to accommodate the frame. 50 The roadway in this construction can be made in the same manner as described above with the other forms of my invention, and also be provided with hand rails etc. which may be folded or collapsed respectively in 55 the above described manner.

The operation of my improved collapsible road-crossing bridge elements will be 60 readily understood from the above description by inspection of the drawings, and it will be seen that when necessity arises a number of these elements may be combined to bridge a crossing without impeding the regular traffic thereunder and without obstructing the view of traffic officers or 65 drivers. The bridge can be set up and re-

moved without much effort and without the use of additional machinery, and placed at any suitable angle to the street so that pedestrians can easily climb the roadway and pass the street crossings in safety. When 70 not in use, the bridge elements can quickly be collapsed and in case of fire a safe passage from a burning building to the street or opposite building may be provided.

It will be understood, that while I have 75 disclosed as an example some of the many forms of constructing my collapsible bridges, many changes such as come within the scope of the appended claims may be made in the general arrangement and in 80 the construction of the minor details of my bridge elements without departure from the spirit of the invention and the principles involved.

Having thus described my invention, what 85 I claim as new, and desire to secure by Letters Patent is:

1. Bridge elements for street crossings, each comprising spaced vertical posts and a 90 roadway, means pivoted between said posts to carry a roadway, means for holding the parts in their position to form a bridge and allowing a folding of the same when not in use, and a means for folding the roadway, 95 said elements so arranged as to avoid obstruction of the view.

2. Bridge elements for road crossings, each comprising a base, a pair of spaced vertical posts on said base, a pair of spaced horizontal girders pivotally secured between 100 said posts, means for supporting the free ends of said girders when said elements form a bridge, a baluster on said girders, a means for holding the parts in their operative position as a bridge and allowing a 105 folding of the same, and a foldable roadway for said bridge.

3. Bridge elements for street crossings, each comprising a roadway, a pair of vertical posts, horizontal girders forming the 110 roadway support pivotally secured between said girders, a foldable baluster on said girders, said roadway composed of a plurality of interconnected slats guided within lateral grooves in said girders, a roller, and a means for folding said roadway upon said 115 roller and unfolding it therefrom.

4. Bridge elements for street crossings, each comprising a pair of vertical posts arranged in spaced relation, a base to which 120 said posts are attached, means for bracing said posts, a pair of horizontally disposed, spaced girders pivotally arranged between said posts, a foldable baluster on said girders, cables attached to said base and to 125 said posts for holding the bridge elements in their bridge forming position and allowing a collapsing of the same when not in use, said girders provided with oppositely disposed inner grooves, a roadway composed 130

of a plurality of interconnected slats traveling and supported with their side edges in said grooves of the girders, a roller, on which said roadway can be wound and unwound therefrom, a pair of cables, a roller for said cables said cables attached at one of their ends to the end slat of said roadway

and adapted to be wound upon said cable roller and to be unwound therefrom, and a crank for operating said cable roller. 10

Signed at New York in the county of New York and State of New York this 8th day of July, A. D., 1926.

PAUL EBELING.
